Atty.

UNITED STATES PATENT OFFICE.

CHRISTOPHER BROWN, OF CHARLEROI, PENNSYLVANIA, ASSIGNOR TO PITTSBURGH PLATE GLASS COMPANY, A CORPORATION OF PENNSYLVANIA.

PROCESS AND APPARATUS FOR APPLYING ABRASIVE TO GRINDING APPARATUS.

Application filed February 9, 1923. Serial No. 618,100.

To all whom it may concern:

Be it known that CHRISTOPHER BROWN, a citizen of the United States, and a resident of Charleroi, in the county of Washington and State of Pennsylvania, have made a new and useful Invention in Process and Apparatus for Applying Abrasive to Grinding Apparatus, of which the following is a specification:

10 The invention relates to a process and apparatus for handling and applying abrasive material such as sand to machines used in grinding plate glass or other substances. Heretofore difficulty has been experienced 15 with various types of graders in securing a mixture of sand which is thick enough particularly at the beginning of the operation. A mixture which is too thin fails to give the desired speed in grinding, and when the 20 runners are first brought into contact with the glass a thick mixture produces a cushioning effect which reduces the danger of breakage due to impact, so that a mixture which is even a little too thick for efficient 25 grinding is desirable at such time. The present invention provides for the thickening of the mixture at any time and is applicable to a wide range of grading apparatus without interfering with the action in the 30 graders. This invention is particularly valuable in that type of graders in which the sand is settled in a solid mass in the grader preliminary to its application to the grinding machine, as in such systems the 35 water which is employed in washing the sand loose and carrying it to the grader invariably dilutes or thins the mixture to too great an extent at the beginning of the operation so that it becomes necessary in such 40 systems to use means other than the grader for applying green (unused) sand to the machine to give the necessary amount of sand.

Even in a suspension system such as that 45 of the Bechtel Patent No. 1,089,895, to which the invention is illustrated as applied in the present case, it is desirable to secure a thicker mixture at the start of the operation, one method of doing this being 50 by the use of additional green sand illustrated in the application of G. W. Oakes, Serial No. 555,378, and in such systems the present invention provides a cheap and effective means for accomplishing this function and also for regulating the proportion

of sand to water for the entire series of grades supplied or for any part of them without interfering with the grading action in the cone tank employed. One embodiment of the invention is illustrated in the accompanying drawings wherein:

Figure 1 is a side elevation, partially in section, showing the complete apparatus and Fig. 2 is a vertical section on an enlarged scale through the concentrating device.

Referring first to the general arrangement of parts as shown in Fig. 1, 1 is a glass grinding table which may be of any approved type and driven in the usual manner, the runners which are employed in connection with the table not being shown, but being similar to those commonly employed in the grinding of plate glass and illustrated in the Bechtel patent referred to; 70 2 is a trough encircling the outer edge of the grinding table and adapted to receive the water and abrasive from such table during the grinding operation; 3 is a sump or collecting receptacle into which the mixture of sand and water from the trough runs by gravity; 4 is a grader into which the mixture of sand and water from the sump is lifted by means of the pump 5 driven from the motor 6; 7 is a pipe for conducting the 75 mixture of sand and water from the grader to the grinding table; and 8 is a concentrator which receives the mixture from the pipe 7 and discharges it to the trough 9 which extends across the grinding table and 80 is provided with a plurality of outlet openings through its bottom.

The grader illustrated is that shown in the Bechtel patent heretofore referred to. This grader has an overflow pipe 10 through 85 which any mud and sand too fine for use is carried to the sewer 11. The abrasive in the tank is graded by the upward flow of water produced by the pump 5, the coarser 90 grades lying at the bottom of the tank and the grades becoming finer and finer from the lower levels to the higher levels. The different grades are withdrawn through the pipes 12, 13 and 14 and through the pipe 15 which has its inner end in the form of a 105 flexible tube adjustable vertically. Intermediate the ends of the tank is an overflow 16 which discharges to the pipe 17 leading back to the trough or gutter 2. In operation, those grades which are not being used 110

are returned to the sump 3, this being accomplished by having those of the pipes 13, 14 and 15 which are not in use discharge to the box 18 and thence to the sump through the pipe 19. This particular grader is only one of a large number which might be employed as one of the parts of the apparatus for carrying out my improved process.

The concentrator 8 is preferably carried 10 above the center of the table 1 upon the framing which supports the runners, and as illustrated, is made in two parts bolted together as indicated at 20 in Fig. 2. The casing is provided with an inlet 21 to which 15 the pipe 7 discharges; a discharge outlet 22 leading into the trough 9 and an overflow outlet 23 from which the pipe 24 carries the surplus water back to the ditch 2. A valve 25 having the threaded stem 26 serves to 20 regulate the flow through the outlet 22, the valve being raised and lowered by means of the wheel 27 resting upon the top of the overflow casing.

The thickness of the mixture discharged 25 from the concentrator depends upon the amount of opening of the valve 25. When this valve is completely open, all of the mixture from the pipe 7 passes through the outlet 22, but as the valve is closed down 30 and the outflow is throttled, the level in the concentrator rises and part of the water from the pipe 7 passes out through the overflow outlet 23. By lowering the valve a sufficient extent, any desired thickness of 35 the mixture may be secured. As stated in the beginning this thickening of the mixture is particularly desirable at the beginning of the operation, at which time it is desirable to cushion the impact of the runners even though the grinding is not as efficient as would be the case with a thinner 40 mixture. The raising and lowering of the valve has no effect upon the function of the grader itself, and if desired, the concentrator 45 may be used throughout the operation to regulate the thickness of the finer grades as well as that of the coarsest grade. This latter function becomes more important in connection with graders which do not operate as accurately as the Bechtel type and 50 is particularly important in connection with graders where the sand is washed from the grader by a stream of water and in which it becomes difficult to control the proportion 55 of sand and water. The concentrator can be cheaply constructed and the cost of upkeep is low. The lower section of the concentrator and the valve, which are the 60 only parts to wear are of cheap construction and require replacement only when

completely worn out as the action of the valve is merely a throttling one and there is no requirement for anything but a rough fit.

What I claim is:

1. The process of applying abrasive to a grinding machine, which consists in collecting the abrasive and water from the machine, returning the mixture to a grader and separating the abrasive into a series of 70 grades, withdrawing therefrom first the coarsest grade of abrasive mixed with water, flowing it to the grinding machine, and eliminating a portion of the water in such withdrawn mixture as it flows from the 75 grader to the machine.

2. The process of applying abrasive to a grinding machine, which consists in collecting the abrasive and water from the machine, returning the mixture to a grader 80 and separating the abrasive into a series of grades, withdrawing therefrom first the coarsest grade of abrasive mixed with water, and causing the mixture so withdrawn to flow to the machine by gravity and during such flow concentrating the mixture by a settling operation, but without removing the abrasive from suspension.

3. In combination a grinding machine including a table, a tank adjacent the table adapted to contain a supply of abrasive and water, a concentrating chamber below the tank having a discharge outlet from its lower portion leading to the table and an overflow outlet from its upper portion, means 90 for regulating the flow from the discharge outlet, means for withdrawing from the grader the coarsest grade of abrasive separate from the other grades and mixed with water, and a conduit for receiving said mixture and discharging to the chamber at a level intermediate that of the discharge and overflow outlets.

4. In combination a grinding machine including a table, a conical grading tank above the table, a concentrating chamber lying above the table and below the tank having a discharge outlet from its lower portion leading to the table and an overflow outlet from its upper portion, means for regulating the flow from the discharge outlet, and a conduit leading from the tank and discharging to the chamber at a level intermediate that of the discharge and overflow outlets.

In testimony whereof, I have hereunto subscribed my name this 22nd day of January, 1923.

CHRISTOPHER BROWN.
